UNITED STATES PATENT OFFICE.

LESLIE NEAL WELLER, OF PINEVILLE, KENTUCKY.

BILLIARD-TABLE POCKET.

Application filed January 26, 1924. Serial No. 688,796.

To all whom it may concern:

Be it known that I, LESLIE NEAL WELLER, a citizen of the United States, residing at Pineville, in the county of Bell and State of Kentucky, have invented certain new and useful Improvements in Billiard-Table Pockets, of which the following is a specification.

This invention relates to billiard-table pockets, the object being to improve the method of securing the pockets in place, doing away with the usual method of tacking the pockets in place.

In the accompanying drawings:

Fig. 1 is a perspective view of a pocket as applied to the table part being broken away; Fig. 2 is a vertical sectional view.

Fig. 3 is a view of the two metal strips.

The numeral 1 indicates the slate bed of the table supported upon the usual wood bed 2. The edges of the beds 1 and 2 are cut as usual to form the throat leading to the pocket 3. Arranged around the throat is a semi-circular metal strip 4 having an upturned outer edge 5. In applying the pocket, the leather strip 6 forming the upper edge of the pocket is placed upon the strip 4, after which a semicircular metal strip 7 of the same general shape as the metal strip 4 is placed over the leather strip 6, and secured in place by suitable fastening means 8. The upturned edge 5 of the lower strip is then bent down over the outer edge of the upper metal strip 7 securely holding the inner edge of the pocket in place.

The outer edge of the pocket is secured to the usual guard-rail 9 by means of a leather

strip 10 which is looped over the guard-rail, the two edges 11—11 being brought together over the upper edge of the pocket.

By securing the inner edge of the pocket to the table as described, the pocket is firmly held in place against the resistance of the balls dropping in place, preventing the pocket from being torn from its fastening means, as is often the case when the pocket is secured in the usual manner by tacking. Furthermore, the pocket is easily replaced without injury to the pocket.

I claim:

1. In a billiard-table, the combination with the table bed having a curved pocket recess, an outwardly curved rail, a pocket having its outer edge supported by said outwardly curved rail, and two semi-circular metallic strips arranged around the upper edge of the circular recess adapted to receive and secure the inner portion of the pocket to the curved recess.

2. In a billiard-table, the combination with the table bed having a curved pocket recess, an outwardly curved rail, a pocket having its outer edge supported by said outwardly curved rail, and two semi-circular metallic strips arranged around the upper edge of the circular recess of the table bed, one of said strips provided with a flange along its outer edge adapted to engage the companion strip for securing the inner edge of the pocket therebetween, and means for fastening said semi-circular strips to the table bed.

In testimony whereof I affix my signature.

LESLIE NEAL WELLER.
